UNITED STATES PATENT OFFICE.

WILLIAM WILLIS WHEELER, OF JACKSONVILLE, FLORIDA.

TRACK CONSTRUCTION.

1,404,414.

Specification of Letters Patent. Patented Jan. 24, 1922.

Application filed February 17, 1921. Serial No. 445,806.

To all whom it may concern:

Be it known that I, WILLIAM WILLIS WHEELER, a citizen of the United States, and a resident of Jacksonville, in the county of 5 Duval and State of Florida, have invented certain new and useful Improvements in Track Construction, of which the following is a specification.

My invention relates generally to track 10 construction and particularly to a track construction specially designed for use in the system of planting, cultivating and gathering of crops embodied in my pending application, Serial No. 387,215, filed June 7, 1920. 15 It is a purpose of my invention to provide a track construction which is simple, inexpensive and extremely durable to withstand the weight and wear of machinery passing over the tracks during the planting, cultivating and harvesting of crops.

I will describe two forms of tracks embodying my invention and will then point out the novel features thereof in claims.

In the accompanying drawings:

25 Figure 1 is a fragmentary view showing in top plan one form of track in applied position within a field.

Figure 2 is a vertical sectional view showing the tracks in applied position within 30 a field.

Figure 3 is a fragmentary view showing in side elevation a portion of one of the track rails and supporting means therefor.

Figure 4 is a transverse sectional view 35 taken on the line 4—4 of Figure 3.

Figure 5 is a fragmentary perspective view showing the manner in which a rail is arranged as with respect to the joint of any two base sections.

40 Figure 6 is a detailed perspective view of one of the connecting bars for connecting the base section.

Figure 7 is a vertical sectional view showing a modified form of base in applied position within the earth.

Similar reference characters refer to similar parts in each of the several views.

Referring specifically to the drawings and particularly to Figures 1 and 2, T and T' 50 designate a pair of tracks, over which farming machinery is adapted to move. These two tracks are only two of a number of similar tracks which are adapted to be arranged at regular intervals throughout the area 55 of a field so as to divide the field into a plu-

rality of independently workable gardens, as more fully described and shown in my pending application heretofore referred to. The tracks T and T' are made up of three rails, the intermediate rail constituting one rail 60 of either of the two tracks. Each rail R is supported upon a base or supporting member B which is co-extensive in length with the rail and of substantially the same thickness. As shown in Figures 3, 4 and 5, each 65 base member is made up of a plurality of companion sections designated at 15 and 15^a arranged end to end and interlocked at their confronting edges by a tongue and groove connection designated at 16 in Figure 4. As 70 shown in Figure 2, each section 15 or 15^a is provided with a relatively wide base 17, and a groove 18 in its upper edge which is co-extensive in length with the section. As 75 shown in Figures 1 and 5, the groove 18 is arranged centrally of the upper edge and is of substantially U-shape in cross section for the reception of a correspondingly shaped tongue 19 formed on the under side of the rail R. The tongue 19 is likewise arranged 80 centrally of the under side of the rail R so that the portions of the rail at opposite sides of the tongue engage corresponding portions on the upper edge of the base section with the tongue within the groove thereby forming 85 a substantial support for the rail and at the same time preventing lateral movement of the rail with respect to the section.

To maintain the base members B in spaced parallel relation, I provide connecting bars 90 C at frequent intervals along the length of the track, such bars being rigidly connected with the base members by arms 20 partially imbedded within the base sections and extending from the confronting sides of the 95 sections at corresponding points. The opposite ends of any one connecting bar C are slotted as shown in Figure 6 for receiving bolts 21 carried by the arms 20 thereby permitting of the slight adjustment of the connecting bar as with respect to the base members, and a secure locking of the connecting bar to the base members after such adjustment has been made.

In practice, the base members B are made 105 of any suitable material, for instance reinforced concrete, each base section 15 or 15^a being formed at one end with a tongue and at the opposite end with a correspondingly shaped groove so that when in assembled 110

2
 position the tongue and groove connection between any two base sections prevents lateral movement of the sections with respect to each other. The rails R in applied position upon the base members are arranged so that the joint between the two rail sections is disaligned with respect to the joint of any two base sections. This arrangement is clearly shown in Figures 3 and 5, the advantage being that the rails serve to further lock any two adjacent base sections, while the base sections serve to prevent lateral displacement of any two rail sections. This arrangement in conjunction with the metallic connecting bars provides a track of extremely substantial and durable construction for the supporting of heavy farming implements thereon during the planting, cultivating and harvesting of crops between the rails of the track.

Referring now to Figure 7, I have here shown a slightly modified form of base member which is designated at B'. This base member B' is constructed the same as the base member B with the exception that it is of smaller dimension from the upper edge to the lower edge so as to be imbedded only for a short distance within the ground. This base member is designed to be used in a warm country where the soil does not become frozen. The base members B are especially designed for use in cold climates where a relatively thick stratum of earth becomes frozen. It is to be particularly noted that the base members B are of such dimension

as to extend into the ground for a considerable distance, preferably to a depth beneath the frozen stratum of earth.

Although I have herein shown and described only two forms of track construction embodying my invention, it is to be understood that various changes and modifications may be made herein without departing from the spirit of the invention and the spirit and scope of the appended claims. 40 45

What I claim is:

1. In a track construction, base members spaced apart and comprising sections arranged end to end and having tongue and groove connections on their confronting ends for locking any two adjacent sections against relative lateral movement, means for rigidly connecting said members, rails supported upon and disposed in parallel relation to the upper edge of said members, and a tongue and groove connection between said rails and members. 50 55

2. In a track construction, spaced base members comprising sections arranged end to end and having tongue and groove connections at their ends, arms formed on the confronting sides of said members, connecting bars rigidly connecting said arms, grooves formed on the upper edges of said members, rails supported on said members and disposed in parallel relation thereto, and tongues formed on said rails and seating within said grooves. 60 65

WILLIAM WILLIS WHEELER.
